PATENTED MAY 7, 1907.

C. D. VORIS.

CORRUGATED METAL CULVERT.

APPLICATION FILED OCT. 6, 1906.

UNITED STATES PATENT OFFICE.

CLIFFORD D. VORIS, OF CRAWFORDSVILLE, INDIANA, ASSIGNOR TO FLORA M. VORIS, OF CRAWFORDSVILLE, INDIANA.

CORRUGATED-METAL CULVERT.

No. 852,478.

Specification of Letters Patent.

Patented May 7, 1907.

Application filed October 8, 1906. Serial No. 337,989.

To all whom it may concern:

Be it known that I, CLIFFORD D. VORIS, a citizen of the United States, residing at Crawfordsville, in the county of Montgomery and State of Indiana, have invented a new and useful Corrugated-Metal Culvert, (Case B,) of which the following is a specification.

This invention relates to sheet-metal culverts of that general class designed for use beneath railway tracks, road-ways and the like or in the construction of sewers, well-curbings, conduits and similar structures.

The object of the invention is to provide a corrugated sheet-metal culvert formed of a plurality of sections capable of being readily united to permit the formation of culverts of different lengths and which may be compactly assembled for transportation or shipment.

20 A further object is to provide the overlapping ends of the culvert sections with laterally extending flanges having perforations formed therein for the reception of securing bolts.

25 A still further object of the invention is to generally improve this class of devices so as to increase their utility, durability and efficiency.

With these and other objects in view the invention consists in the construction and novel combination and arrangement of parts hereinafter fully described, and illustrated in the accompanying drawings, it being understood that various changes in form, proportions and minor details of construction may be resorted to within the scope of the appended claims.

In the accompanying drawings forming a part of this specification: Figure 1 is a side elevation partly in section of a culvert constructed in accordance with my invention.

40 Fig. 2 is a transverse sectional view taken on the line 2--2 of Fig. 1. Fig. 3 is a longitudinal sectional view illustrating a modified form of the invention. Fig. 4 is a similar view illustrating a still further modification.

Similar numerals of reference indicate corresponding parts in all of the figures of the drawings.

50 The improved culvert consists of a plurality of sections of any desired length and each preferably formed of a single sheet of metal or other suitable material bent into a sub-

stantially cylindrical shape and provided with spaced circumferential corrugations 6. 55

The corrugations 6 preferably terminate short of the adjacent longitudinal edges of the metal forming the culvert sections so as to permit the metal to be bent upon itself to produce terminal hooks 7 and 8 which inter- 60 engage and thus form a lap-joint at the juncture of said edges.

The metal on each side of the lap-joint is rolled, stamped or otherwise pressed laterally to produce longitudinally disposed stop- 65 ribs 9 which bear against the closed ends of the hooks 7 and 8 and thus serve to prevent accidental displacement of the longitudinal edges of the culvert sections. The corrugations 6 also terminate short of the opposite 70 ends of each section thereby to produce terminal bearing collars 10 and 10' the interior and exterior walls of which are smooth and unobstructed and adapted to over-lap the corresponding bearing collar of an adjacent 75 section.

Secured to the bearing collars 10 and 10' in any suitable manner as by rivets or similar fastening devices 11 are angle irons 12 the laterally extending flanges 13 and 14 of which 80 are provided with spaced perforations 15 for the reception of securing bolts 16. The flange 13 of one of the angle irons is disposed in alignment with the adjacent collar 10 while the flange 14 is spaced inwardly on the 85 collar 10' so as to permit the end of the collar 10' to over-lap the collar 10 and thus insure a water tight joint between the same.

If desired the angle irons 12 instead of extending entirely around the culvert may be 90 formed in short sections and riveted or otherwise secured to the interior or exterior walls of the culvert, the result accomplished being the same in both cases.

In assembling the sections comprising the 95 culvert the bearing collar of one section is inserted within the collar of an adjacent section and said sections forced together until the flange 13 engages the flange 14 after which the bolts 16 are threaded through the perforations in the flanges and secured by the clamping nuts, as will be readily understood.

In Fig. 3 of the drawing there is illustrated a modified form of the invention in which the angle irons 17 and 18 are riveted or otherwise 105 secured to the interior walls of the culvert sec-

tions, one of said angle irons being substantially **T** shaped in cross section and the other **L** shaped.

In Fig. 4 of the drawing the adjacent longitudinal edges of the metal forming each culvert section are secured together by angle irons 19 and 20 similar in construction to the angle irons 12, the flanges of the angle irons 19 and 20 being pierced by suitable fastening bolts indicated at 21 so that said sections may be readily detached and compactly stored for transportation or shipment.

It will of course be understood that while the short sections of culverts for instance the two and three foot lengths, may be formed of a single piece of metal the longer sections may be constructed of two or more pieces of metal united in any suitable manner.

Having thus described the invention what is claimed is:

1. A culvert comprising a plurality of detachable telescopic sections, each having its opposite longitudinal edges bent to form terminal interengaging hooks constituting a lap-joint, the metal on each side of the lap-joint being pressed laterally to form substantially **V** shaped longitudinal stop-ribs, flanges permanently secured to and extending laterally from the over-lapping ends of the sections, and means engaging the flanges for clamping the sections in alignment with each other.

2. A culvert comprising a plurality of detachable corrugated telescopic sections with the corrugations terminating short of the opposite ends of the sections to form bearing collars, said sections being each formed of a

single piece of metal bent into substantially cylindrical shape and having its adjacent longitudinal edges provided with interengaging hooks constituting a lap-joint the metal on each side of the lap-joint being pressed laterally to form a substantially **V** shaped longitudinal stop-rib, flanges permanently secured to the terminal collars and having spaced perforations formed therein, and securing bolts passing through the perforations in the flanges for locking the sections in alignment with each other.

3. A culvert formed of a plurality of detachable corrugated telescopic sections with the corrugations terminating short of the opposite ends of the sections to form bearing collars, a plate permanently secured to one of the collars and provided with a laterally perforated flange disposed in alignment with the adjacent end of said collar, a similar plate permanently secured to and spaced inwardly from the end of the opposite collar and having its flange provided with perforations adapted to register with the perforations in the adjacent flange, and securing bolts passing through said perforations for locking the sections in alignment with each other.

In testimony that I claim the foregoing as my own, I have hereto affixed my signature in the presence of two witnesses:

CLIFFORD D. VORIS.

Witnesses:

BRUCE HAINES,
ROBERT H. CISSEL.
